[57] CLAIM

The ornamental design for a tricycle, substantially as shown and described.

DESCRIPTION

FIG. 1 is a left front perspective view of a tricycle showing my new design;

FIG. 2 is a right rear perspective view thereof;

FIG. 3 is a fragmentary perspective view of a tricycle showing a second embodiment of my new design, it being understood that the tricycle body has been omitted for ease of illustration, wherein the only difference resides in the handle bar structure; and

FIG. 4 is a fragmentary perspective view of a tricycle showing a third embodiment of my new design, it being understood that the tricycle body has been omitted for ease of illustration, wherein the only difference resides in the handle bar structure.
